MACHINE FOR OPERATING UPON SOLES

Fred V. Hart, Lynn, Mass., assignor to United Shoe Machinery Corporation, Borough of Flemington, N. J., a corporation of New Jersey

Application April 5, 1938, Serial No. 200,154

13 Claims. (Cl. 12—21)

This invention relates to machines for shaping soles and is illustrated herein as embodied in a machine of the type disclosed in U. S. Letters Patent No. 1,939,750, granted on December 19, 1933 upon an application of E. E. Winkley.

Soles are commonly shaped so as to fit the bottom of a shoe for which they are intended by the use of a machine of the type mentioned above which comprises a form about which the sole, and particularly the shank portion of the sole, is bent into the required longitudinal and transverse curvatures. Frequently in the use of a machine of this type, the heel part or heel end portion of the sole is displaced out of the original plane of the sole blank to impart the desired angular relation between the forepart and shank. For this reason the form about which the shank of the sole is shaped and the heel end portion clamping means are independently mounted and are separated by a slight gap which, in being bridged by the sole, may cause a slight irregularity in the contour of the sole edge. The same tendency also arises if, as is usually the case, the heel end portion is clamped in a flat condition while the contiguous portion of the shank is curved transversely about the form.

In view of the foregoing, it is one object of this invention to improve the regularity of the contour of soles at the junction of their shanks and heel end portions upon being shaped in a machine of the type referred to above.

Accordingly, the invention provides as one feature, in a machine having a form about which a sole is to be shaped, means for supporting and shaping the heel part of a sole comprising a member which overlies the heel end of the form and the sole engaging surface of which is substantially continuous with that of the form. This construction not only permits relative movement between the form and member heightwise thereof, but also provides an uninterrupted sole supporting surface, when the form and member are in their operative relation, thereby insuring against any irregularity in the shape of the sole when pressed against the form and member. Preferably, and as herein illustrated, the sole engaging surface of the above-mentioned member, being a continuation of the form, is concavely curved both longitudinally and transversely and a complementary member constituting another element of the above-mentioned clamping means causes the heel end portion of the sole, upon being clamped, to be bent into a concavo-

convex form and hence is cupped so as to fit the slightly convex heel seat of a shoe.

The forepart and heel end portion of a sole now having been clamped, the shank may be pressed into conformity to the shape of the form and the portion of the member which overlies the form, by a conforming tool having a sole engaging surface substantially complementary to those of the form and member.

In the construction of a certain type of shoe the heel, often a wood heel, is provided with a shallow groove in its breast adjacent to the attaching surface, which groove receives the stub heel end portion of the sole and thus locks the sole in the vicinity of the heel breast line against any heightwise displacement. Soles of this type are commonly known and will be referred to hereinafter as "Breastlock soles."

Because a Breastlock sole has at best merely a stub heel part, it is unlikely that the heel end portion of such a sole, when placed in a machine of the type mentioned above as constructed for operating upon conventional soles, will come within the field of action of the heel part clamping members.

Accordingly, another object of the invention is to extend the usefulness of a machine of the type referred to above by adapting it for operating upon Breastlock soles.

To this end, the invention provides as another feature, an extension or jaw on the upper heel part clamping member which is arranged to cooperate with the lower member overlying the heel end of the form both to grip the stub heel end portion of the sole and impart to it the required transverse and longitudinal curvatures.

In connection with the use of the heel end clamping and shaping means described above as adapted for operating upon Breastlock soles, the illustrated conforming tool, in accordance with another feature of the invention, is recessed at its heel end to receive the jaw and extension of the upper clamping member, the shoulders of the conforming tool at each side of this recess being arranged to press the marginal portions of the sole at each side of the jaw and extension toward or into engagement with the sides of the form and lower clamping member.

These and other objects and features of the invention will appear more fully from the following description when read in connection with the accompanying drawings and will be pointed out in the appended claims.

In the drawings,

Fig. 1 is a view in front elevation of a part

of an illustrative machine embodying the invention;

Fig. 2 is a perspective view of a sole which has been operated upon in the illustrated machine;

Fig. 3 is a view in front elevation and partly in section illustrating the form and sole shaping members in their operative relation;

Fig. 4 is a sectional view, the section being taken along the line IV—IV in Fig. 3;

Fig. 5 is a perspective view of the upper member for clamping and shaping the heel end portion of a sole;

Fig. 6 is a view in perspective of the lower sole clamping and shaping member with which that shown in Fig. 5 cooperates; and

Fig. 7 is a view in perspective of the conforming tool.

As a machine of the type in which the present invention is illustrated herein as embodied is completely disclosed in the above-mentioned Winkley patent, to which reference may be made for a complete description of corresponding parts of the present machine, only such of its parts as are necessary for an understanding of this invention will be disclosed herein. Parts of the illustrated machine which will be readily identified in the above-mentioned Winkley patent comprise tables 10, 12 the former being adapted to support the forepart of a form 14 the shank portion of which is supported by a lug 16 integral with the machine frame, and a clamp 18 removably fixed in a head 10 mounted for movement toward and away from the table 10 to cause the clamp 18 to hold the forepart of the sole against the form 14.

To adapt the machine for operating upon Breastlock soles as well as conventional soles, the illustrated machine includes improved means for shaping and clamping the heel end portion of a sole of any type, this means comprising lower and upper members 20, 22 having jaws or extensions 24, 26, respectively, adapted to grip and shape the heel end portion of any sole, such as a Breastlock sole for example, the heel end portion of which is so short that it does not extend between the portions of the members 20, 22 from which the jaws 24, 26 extend.

A sole to be operated upon is placed on the form 14 and member 20 in the desired position as indicated by gages of the type disclosed in the above-mentioned Winkley patent. At this time, as will be understood by reference to the Winkley patent, the form 14 and member 20 occupy positions below and in front of the clamp 18 and member 22 for the sake of convenience to the operator in placing soles thereon. Upon treading the machine, the tables 10 and 12 carrying the form 14 and member 20 are swung to a position directly underneath the clamp 18 and member 22 which then descend together to clamp the fore and heel parts of the sole.

Thereupon, while the fore and heel parts of the sole are clamped, the members 20 and 22 are bodily lowered with respect to the form 14 until the sole engaging surfaces of the form 14 and member 20 are substantially continuous as illustrated in Fig. 3. Then a plunger 28 having connected thereto, by means of pivotal connections similar to those to be found in the above-mentioned Winkley machine, a conforming tool 30 is moved downwardly to cause the shank portion of the sole and a part of the forepart contiguous thereto to be shaped about the form. Thus, the sole is so shaped as to take the form

illustrated in Fig. 2, when removed from the machine, the sole having been shaped both transversely and longitudinally with a continuous curvature throughout the shank and heel end portions. If the sole in question is of the conventional type its heel end portion, as indicated in dotted lines in Fig. 2, will be cupped continuously with the curvature of the adjacent portion of the shank.

Having described the machine and its operation in a general way, its novel features will now be described in greater detail. The members 20 and 22 are provided with substantially complementary sole engaging surfaces which transversely thereof are convex and concave, respectively. Longitudinally, these surfaces have a sinuous form as indicated in Figs. 1 and 3. The sole engaging surfaces of the jaw 24 and form 14 are continuous with each other when in their operative relation, the latter being cut away at 32 to receive the jaw 24 which overlies the heel end of the form 14, and which together with the form constitutes a substantially uninterrupted support for the sole thereby insuring an even contour in the edge of the sole pressed against them.

The shaping of the heel end portion of the sole, either of the conventional or the Breastlock type, is effected by the cooperation of the member 20 with the member 22 the jaw 26 of the latter being provided with lips 33 extending downwardly at each side of the jaw 24 so as to operate upon a substantial width of the shank of the sole and to impart a rather abrupt transverse curvature, continuous with that of the remainder of the shank, to the portion of the shank in the vicinity of the heel breast line. Thus, if a Breastlock sole is being operated upon, its heel end portion when gripped between the jaws 24, 26 is prevented from being displaced owing to the action of the conforming tool 30 and will have the required shape imparted to it.

The member 22 is removably fixed to a head 34 which is movable toward and away from the table 12 to cause the heel end portion of the sole, as described above, to be clamped against and formed about the member 20 which is pivotally mounted on a base plate 36, carried by the table 12, by means of a knuckle joint 38 which permits the member 20 to tilt into parallelism with the member 22 thereby equalizing the pressure over the entire clamped area of the heel end portion of the sole. In case a Breastlock sole is being operated upon, the rear ends of the members 20 and 22 engage each other, as at 40 (Fig. 3), to prevent excessive tilting of the member 20 beyond a position of parallelism with the member 22, which otherwise might occur because of the lack of any sole material between the central portions of the members 20 and 22. Fixed in the member 20 is a screw 42, the head of which is housed in a recess 44 in the plate 36, for holding the plate and member 20 in assembled relation.

The illustrated conforming tool 30 is provided with a recess substantially complementary to the sole engaging surface of the form 14 and at 46 is adapted to hold a narrow portion of the forepart of the sole contiguous to the shank against the form. The tool 30 also comprises laterally spaced shoulders 48 which are arranged closely to embrace the sides of the shank portion of the form 14.

The tool 30 is recessed at its central rear portion, as indicated at 50, so as to avoid engaging

the jaw 26 when the tool is moved to its operative position. The shoulders 48, however, on each side of the recess 50 forwardly of the jaw 26 engage portions of the sole which bridge the junction of the form 14 and jaw 24 and hence cooperate with the lips 32 to press the sides of the sole shank in the vicinity of the heel breast line into the desired shape continuously along the length of the sole.

10 It will now be understood that the illustrated machine is adapted to impart longitudinal and transverse curvatures to the shank and heel end portions of a sole whether the sole is of the Breastlock type or of the conventional type. 15 Moreover, regularity in the longitudinal curvature of the outer edges of the sole between its shank and heel end portions is insured because of the overlapping relation of the jaw 24 and form 14, there being no break in the continuity 20 of the support for the sole between its shank and heel end portion.

Having thus described my invention, what I claim as new and desire to secure by Letters Patent of the United States is:

25 1. In a machine for shaping soles, sole supporting means comprising a form adapted to support the shank of a sole and a member normally spaced from and overlying the heel end of said form, said member being adapted to support the heel end portion of the sole, a support for said member mounted for movement heightwise of said form into such a position that the sole engaging surfaces of said form and member are substantially continuous with each other, 30 and a conforming tool, said tool and means being mounted for movement relatively to each other to cause the sole disposed therebetween to be pressed against said form and member.

2. In a machine for shaping soles, sole supporting means comprising a form and member mounted for movement relatively to each other heightwise thereof and adapted to support the shank and heel end portions of a sole, said member having a jaw normally spaced from and overlying the heel end of said form, and conforming means, said sole supporting means and conforming means being mounted for movement relatively to each other to cause a sole disposed therebetween to be pressed against said form and member.

50 3. In a machine for operating upon soles, sole supporting means comprising a form and a member mounted for movement heightwise of said form into overlapping relation with the heel end portion thereof, conforming means shaped and arranged to cooperate with said form and member to impart transverse and longitudinal curvatures to the shank and heel end portions of the sole, and means for successively moving said member into such a position that its sole engaging surface is substantially continuous with that of the form and for moving said conforming means into engagement with a sole on said form and member.

65 4. In a machine for operating upon soles, a form adapted to support and shape the shank of a sole pressed thereagainst, members normally spaced from said form for clamping the heel end portion of the sole, said members being mounted for movement together into such a position that the sole engaging surface of one of said members is substantially continuous with that of the form, and means for pressing the sole about said form and the last mentioned member.

70 5. In a machine for operating upon soles, a

form, a conforming member cooperating with said form to impart transverse and longitudinal curvatures to the shank of a sole, means for clamping the heel end portion of the sole comprising jaws overlying said form and adapted to impart a curvature to the heel end portion of the sole continuous with that of the shank.

6. In a machine for operating upon soles, a form adapted to support and shape the shank of the sole, means for clamping the heel end portion of the sole comprising a member having a sole engaging surface substantially continuous with that of said form, and a conforming tool mounted for movement toward said form and member to bend the sole thereabout, said member being mounted to pivot in response to pressure of the sole thereagainst.

7. In a machine for shaping soles, a form adapted to support the shank of a sole, clamping members having jaws arranged to grip and impart a transverse curvature to the heel end portion of the sole, one of said members being mounted to pivot into engagement with the other in response to the pressure of the sole thereagainst, and means cooperating with said form to impart transverse and longitudinal curvatures to the shank of the sole.

8. In a machine for shaping soles, a form adapted to support the shank of a sole, members mounted for movement toward each other to clamp and shape a portion of the sole overlying the heel end of said form, and a conforming tool cooperating with said form and one of said members to impart a transverse curvature to the sole, said conforming tool being recessed to receive the other of said members.

9. In a machine for shaping soles, a form adapted to support the shank of a sole, clamping members having jaws arranged to grip and impart a transverse curvature to a portion of the sole overlying the heel end of said form, a conforming tool mounted for movement toward said form to shape the shank of the sole thereabout, said tool being recessed to receive one of said jaws and having a shoulder arranged to press a margin of the shank toward the other jaw and the form.

10. In a machine for shaping soles, a form adapted to support the forepart and shank of a sole, means for clamping the forepart of the sole against said form, means for clamping a portion of the sole overlying the heel end of said form, said last-mentioned clamping means being movable heightwise of the sole to impart the angular relation between the shank and forepart of the sole which they are to have in a finished shoe, and means cooperating with said form to impart longitudinal and transverse curvatures to the shank of the sole.

11. In a machine for shaping soles, a form adapted to support the forepart and shank of a sole, plural means for clamping the forepart of the sole and a portion thereof overlying the heel end of said form, said means being relatively movable heightwise of the sole to impart the angular relation between the shank and forepart of the sole which they are to have in a finished shoe, and a conforming member cooperating with said form to shape the shank of the sole about said form.

12. In a machine for shaping soles, a form adapted to support the forepart and shank of a sole, means for clamping the forepart of the sole against said form, means for clamping the heel end of the sole comprising a support and a clamp-

75

ing member movable toward said support to grip and shape the heel end portion of the sole, said support and clamping member overlying the heel end of said form and being mounted for movement bodily heightwise of the sole into such a position that the sole engaging surfaces of said form and support are substantially continuous with each other, and a conforming member mounted for movement toward said form to shape the shank of the sole thereabout.

13. In a machine for operating upon soles, a

form adapted to support and shape the shank of the sole, means for clamping the heel end portion of the sole comprising a member mounted to swing about an axis and having a sole engaging surface substantially continuous with that of said form and a second member adapted to engage the sole and the first mentioned member at opposite sides of said axis, and a conforming tool mounted for movement toward said form and first mentioned member to shape the sole thereabout.
